UNITED STATES PATENT OFFICE.

CHRISTIAN M. SLETTEN, OF CHIMNEY ROCK, WISCONSIN.

MULTIPLE STANCHION.

1,099,623.

Specification of Letters Patent.

Patented June 9, 1914.

Application filed May 3, 1913. Serial No. 765,334.

To all whom it may concern:

Be it known that I, CHRISTIAN M. SLETTEN, citizen of the United States, residing at the town of Chimney Rock, in the county of Trempealeau and State of Wisconsin, have invented certain new and useful Improvements in Multiple Stanchions; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to multiple stanchions, and more particularly to that class of multiple stanchions adapted to be controlled by a common mechanism, so that all of the stanchions may be operated simultaneously.

The object of this invention is to provide a multiple stanchion adapted to be durable, useful and capable of being adapted to any building.

A further object of this invention is to provide a multiple stanchion, all of the restraining devices of which may be simultaneously operated to restrain or free an animal, or in which any desired number of the restraining devices proper may be actuated, or remain inoperative.

A further object of the invention is to provide a stanchion adapted to facilitate the housing of a number of animals by eliminating the usual draw-backs of such devices.

With these and other objects in view, this invention consists in the peculiar construction and combination of the parts of a multiple stanchion as hereinafter described and more particularly pointed out in the appended claims.

Referring to the drawings wherein similar reference numerals indicate similar parts wherever used, Figure 1 is a perspective view of the multiple stanchion. Fig. 2 is a front elevation of one of the stanchion units. Fig. 3 is a vertical section on line 3-3, Fig. 2. Fig. 4 is a detail section through the lower part of the restraining device showing the spring. Fig. 5 is a detail section through one of the guards showing the spring. Fig. 6 is a vertical section on line 6-6 of Fig. 2.

Reference numeral 7 represents a sill of concrete or the like formed on the floor of

a stable. Secured by bolts or embedded into the sill are a plurality of uprights 8 preferably formed of piping and having at their upper ends a flattened portion 9. Below the flattened portion 9, the uprights are provided with threaded T-shaped nipples 10, which receive additional piping 11 adapted to define the different stalls as shown in Fig. 1.

Adjacent the beginning of the flattened portion is a non-rotatable shaft 12, which is prevented from movement in any direction. At its outer end the shaft 12 is provided with a cog-wheel 13, loosely mounted thereon and adapted to be rotated by means of a hand-wheel 14. Above the shaft 12, the flattened portion 9 is provided with a bearing adapted to receive a rotatable shaft 15, which is prevented from lateral movement by collars 16-16. At its outer end the shaft 15, is provided with a cog-wheel 17, fast thereon and meshing with the cog-wheel 13, and adapted to be controlled by a pawl 18, mounted on a bracket 19. It will thus be seen that a movement of the handle 14 will cause the cog-wheel 13 to rotate the cog-wheel 17, which will rotate the shaft 15, subject to the action of the pawl 18. Secured to the shaft 15, and rotating therewith are collars 20-20. Wound around the collars 20-20 and fastened at one end thereto are chains 21-22, the purpose of which will be hereinafter set forth. Midway between the uprights the shaft 15, is provided with two chains 23-24 which are wound around the shaft 15, and then pass downwardly through a tube 25, placed transversely through the shaft 12. The purpose of these chains will be hereinafter described.

Pivots supported to the sill 7 by a chain 26 is a restraining device or stanchion composed of two pivotally connected (at 26') bow-shaped sections 27-28, which are adapted to be held apart at their upper ends 29-30 by means of a leaf spring 31, inserted above the pivot (see Fig. 4.) The chains 23-24 are connected to the upper portions 29-30 of the stanchion, as at 32. The chains are so arranged that when they are wound up upon the shaft 15, they bring the parts 27-28 of the stanchion together against the action of the spring 31, by means of the inward pull upon the parts 29-30, causing said parts to move from the position shown in dotted lines 27'-28' and

29'-30' shown in Fig. 2. The pull exerted by the chains also raises the stanchion the full length of the chain 26, thus raising it a slight amount to the position 5 shown in full lines in Fig. 2.

Secured to the uprights 8 at a point near the sill are formed brackets 33. Pivotedly supported at 34 upon said brackets are members 35, extending upwardly and terminating in a U-shaped forked portion comprising arms 36-37. These arms extend upwardly to a point level with the upper surface of the shaft 12, where the members 36-37 are joined by a pivoted yoke member 38, which bears slidably upon the upper surface of the shaft 12. Placed within the bracket 33 is a leaf spring 39, which bears against the upright 8 and the members 35 and forces the members 35 outwardly and 20 away from the upright 8 toward the center of the shaft 12, the member 38 sliding along the shaft 12.

The chains 21-22 heretofore described are wound about the rotatable shaft 15, and 25 pass downwardly under pulleys 40 supported by brackets 41, upon the uprights 8. From this point the chains run inwardly and are fastened at 21'-22' to the yoke members 38-38 in such a manner that when 30 the chains 21-22 are wound on the shaft 15, the member 35 takes the position shown in full lines in Fig. 2. By rotating the shaft 15 to close the stanchions 27-28 the chains controlling the members 35 will also be 35 wound up and will cause the members 35 to be drawn toward the upright 8 against the action of the spring 39 and will come to rest at a point about half-way between the stanchions and the uprights, this position 40 being regulated by the length of the chain. The function of these members 35 is to form a guard upon each side of the stanchions to prevent an animal from inserting its head into the space between the 45 stanchions and the uprights.

When the stanchion is in an open position the guards take the position shown in dotted lines 35'-35' in Fig. 2, due to the spring forcing the members outwardly.

50 Should it be desired to leave a stanchion in closed position to confine an animal, while the other stanchions are opened, there is provided a pin 42, which is inserted through the links of the chains 23-24 so that the pin 55 will bear against the upper part of the tube 25, thus preventing further movement of the stanchion members 27-28, while the other stanchions are free to move. By rotating the shaft 15, the chains will be wound or 60 unwound upon the shaft 15, thus actuating the guards and the stanchion members of the several restraining units.

Considerable variation of the specific details of this invention may be resorted to 65 without departing from the spirit thereof.

What I claim as new is:—

1. In a restraining device, the combination with a plurality of uprights, of a plurality of shafts mounted thereon, a stanchion between said uprights, guards for said stanchions, and means carried by one of the shafts to control said stanchion and said guards. 70

2. In a restraining device, the combination with a plurality of uprights, of a rotatable shaft mounted thereon, a stanchion between said uprights, guards for said stanchion, said guards comprising members having a U-shaped portion, brackets upon said uprights for pivotally supporting said guard members, means for forcing said guard members toward the stanchion, and means carried by said shaft and members to force the said members away from the stanchion against the action of said inwardly forcing means. 80

3. In a restraining device the combination with a plurality of uprights, of a rotatable shaft mounted thereon, a stanchion between said uprights, guards for said stanchion, said guards comprising members having a U-shaped portion, means upon said uprights for forcing said guard members toward the stanchion, said means comprising a U-shaped leaf-spring bearing against 95 the guard and the upright, and means carried by said shaft and the members to force the said members away from the stanchion against the action of said inwardly forcing means. 100

4. In a restraining device, the combination with a plurality of uprights, of a shaft mounted thereon, a stanchion between said uprights, said stanchion comprising members formed with inwardly curving end portions, two of said end portions being flattened to form a bearing, a pivot in said bearing, means carried by the stanchion for forcing the members apart, said means comprising a leaf spring carried by said members above the pivot, and means carried by said shaft, said means comprising flexible connections attached to the said shaft and extending downwardly and fastened to the ends of the stanchion members, whereby a 115 rotation of the shaft will wind the chain about the shaft to pull the stanchion members together against the action of the leaf spring. 110

5. In a restraining device the combination with a plurality of uprights, of a rotatable shaft mounted thereon, a stanchion between said uprights, guards for said stanchion, said guards comprising members having a U-shaped portion, means upon said uprights for forcing said guard members toward the stanchion, said means comprising a U-shaped leaf-spring bearing against the guard and the upright, a non-rotatable shaft on said upright, a yoke connecting the arms 120 125 130

of said U-shaped portion and adapted to slide upon said non-rotatable shaft, a plurality of collars on said rotatable shaft, means carried by said rotatable shaft adapted to force the guards away from the stanchion against the action of the spring, said means comprising a flexible connection fastened to said rotatable shaft and said yoke member, guides for said flexible connection whereby a rotation of the shaft will wind the chain about the shaft to pull the guard members apart against the action of the leaf-spring.

6. In a restraining device, the combination with a plurality of uprights, of a shaft mounted thereon, a stanchion between said uprights, a plurality of members between said uprights forming guards for said stanchion, and means carried by said shaft to control the open and closed position of said stanchion and said guards, the guards in the closed position being near the stanchions.

7. In a restraining device, the combination with a plurality of uprights, of a shaft mounted thereon, a stanchion between said

uprights, a plurality of members between said uprights forming guards for said stanchion, and flexible connections carried by said shaft to control the open and closed position of said stanchion and said guards, the guards in the closed position being near the stanchions.

8. In a restraining device, the combination with a shaft, of a support therefor, a stanchion comprising separable members, a plurality of members forming guards for said stanchion, means for forcing said stanchion members outwardly, means for forcing the guards inwardly, and means carried by said shaft to control the open and closed position of the stanchion members and the guards.

In testimony whereof I have signed my name to this specification in the presence of two subscribing witnesses.

CHRISTIAN M. SLETTEN.
